(57) **CLAIM**

The ornamental design of an RFID tag, as shown and described.

DESCRIPTION

FIG. 1 is a perspective view of an embodiment of the RFID tag illustrating our new design;
FIG. 2 is a top plan view thereof;
FIG. 3 is a front elevation view thereof, the rear elevation being a mirror image thereof;
FIG. 4 is a perspective view of another embodiment of the RFID tag illustrating our new design;
FIG. 5 is a top plan view thereof; and,
FIG. 6 is a front elevation view thereof, the rear elevation being a mirror image thereof.

The broken lines in the drawings represent portions of the RFID tag that form no part of the claimed design.

The left side elevational view, the right side elevational view, and the bottom plan view of the RFID tag are not shown and form no part of the claimed design.
